UNITED STATES PATENT OFFICE.

JOHN H. BURKHOLDER, OF ASHLAND, OHIO, ASSIGNOR, BY DIRECT AND MESNE ASSIGNMENTS, TO WILLIAM V. B. TOPPING, OF ASHLAND, OHIO.

DOOR-HANGER.

No. 833,438.

Specification of Letters Patent.

Patented Oct. 16, 1906.

Application filed November 20, 1905. Serial No. 288,308.

To all whom it may concern:

Be it known that I, JOHN H. BURKHOLDER, a citizen of the United States, residing at Ashland, in the county of Ashland and State of Ohio, have invented new and useful Improvements in Door-Hangers, of which the following is a specification.

My invention relates to improvements in door-hangers, particularly in the provision of improved means whereby the hanger is enabled to be adjusted both vertically and laterally; and it consists in the construction, combination, and arrangement of devices hereinafter described and claimed.

15 In the accompanying drawings, Figure 1 is a front elevation of a door-hanger embodying my improvements. Fig. 2 is a vertical sectional view of the same. Fig. 3 is a detail horizontal sectional view taken on the 20 plane indicated by the line *a a* of Fig. 1, and Fig. 4 is a detail vertical sectional view taken on the plane indicated by the line *b b* of Fig. 1.

The hanger member 1 of my improved door-hanging devices has a vertical arm 2, 25 and a horizontal arm 3 at the upper end of the said vertical arm and which projects laterally from the rear side thereof. At the lower end of the arm 2 is an outwardly-projecting lug 4, and at the outer end of the arm 3 is an upstanding lug 5. The arm 2 has a vertical channel 6 in its outer side, and in the upper side of the arm 3 is a longitudinal channel 7.

35 The door-plate 8 is provided near its upper corners and at its lower end with ears 9, having openings for bolts 10, which are employed to secure the said plate to the door. At the upper end of the said plate is a rearwardly-extending horizontal lip or flange 11 to bear 40 on the upper edge of the door. The upper portion of the said plate is provided on its outer side with a guide-channel 12 for the reception of the vertical arm 2 of the hanger member, the sides of the said channel being provided with inturned flanges 13 to bear against the outer sides of the arm 2, and hence retain 45 said arm in the said channel 12, while permitting said arm to be vertically adjusted in said channel. At the lower end of the channel 12 is an outwardly-extending ear 14.

An adjusting-bolt 15 passes through alined openings in the ears 4 and 14 and serves to connect the hanger member to the plate. The head of the bolt is disposed in the channel 55 6 of the vertical arm of the hanger mem-

ber, and the nut 16 on the bolt bears against the under side of the ear 14. It will be understood that by turning said nut the hanger member will be vertically adjusted in the plate.

60 In the channel of the horizontal arm 3 of the hanger member is a movable block 17, having side shoulders 18, which are engaged by flanges 19 at the sides of the said channel. The said movable block has a screw-threaded 65 opening for the reception of an adjusting-bolt 20, which passes through an opening in and is swiveled to the ear 5. The said movable block is provided on its upper side with an eye 21 for the reception of a bolt 22, 70 which is employed to pivotally connect the lower end of the wheel-housing 23 to the said movable block. It will be understood that by turning the bolt 20 the movable block will be caused to move in the channel of the horizontal arm of the hanger member to effect a lateral adjustment of the hanger member, the plate, and hence also of the door.

75 From the foregoing description, taken in connection with the accompanying drawings, 80 the construction and operation of the invention will be readily understood without requiring a more extended explanation.

Having thus described my invention, what I claim as new, and desire to secure by Letters Patent, is—

1. The combination of a plate for attachment to a door, a wheel-housing, a hanger-arm having a vertical member and a horizontal member, the former connected to the said 90 plate for vertical adjustment, and a movable block attached to the wheel-housing and also connected to the horizontal member of the hanger-arm for horizontal adjustment.

2. The combination of a plate for attachment to a door, a hanger-arm connected to said plate for vertical adjustment and having a horizontal member, and connecting means between the wheel-housing and the horizontal member of the hanger-arm and including 100 an element adjustable on said horizontal member to effect the lateral adjustment of the door.

In testimony whereof I have hereunto set my hand in the presence of two subscribing 105 witnesses.

JOHN H. BURKHOLDER.
